Patented Nov. 28, 1916.

UNITED STATES PATENT OFFICE.

JOHN MILUTIN, OF ALTA LOMA, TEXAS.

ENVELOP.

1,206,125.

Specification of Letters Patent. Patented Nov. 28, 1916.

Application filed April 3, 1916. Serial No. 88,674.

To all whom it may concern:

Be it known that I, JOHN MILUTIN, a citizen of the United States of America, residing at Alta Loma, in the county of Galveston and State of Texas, have invented certain new and useful Improvements in Envelops, of which the following is a specification, reference being had therein to the accompanying drawing.

10 This invention relates to safety envelops and has for its object the production of a simple and efficient envelop which may be readily and conveniently sealed and after once having been sealed, cannot be opened 15 without the same being detected.

Another object of this invention is the production of a simple and efficient means for sealing an envelop wherein the tongues are provided with elastic means for causing 20 the sealing tongues to normally retain an extended position.

With these and other objects in view, this invention consists of certain novel combinations, constructions, and arrangements 25 of parts, as will be hereinafter fully described and claimed.

In the accompanying drawings:—Figure 1 is a plan view of the rear face of the envelop. Fig. 2 is a plan view of the blank 30 from which the envelop is made. Fig. 3 is a section taken on line 3—3 of Fig. 1. Fig. 4 is a section taken on line 4—4 of Fig. 1. Fig. 5 is a detailed perspective of a portion of the closure flap of the envelop. Fig. 6 35 is a detailed perspective of the under face of a portion of the closure flap.

Referring to the accompanying drawings by numerals it will be seen that 1 designates the body of the envelop which is provided 40 upon the bottom thereof with a bottom closure flap 2 and upon the sides thereof with a pair of end closure flaps 3. A top closure flap 4 is also integrally secured to the body 1, as illustrated in Fig. 2 of the 45 drawings.

The end closure flaps 3 are provided with elongated slots 5 and these end flaps are adapted to be folded upon the body of the envelop as shown in Fig. 1. The bottom closure flap 2 is provided with an elongated slot 6 and this bottom closure flap is adapted to be folded over the end closure flaps, as illustrated in Fig. 3 of the drawings. The bottom closure flap 2 is provided with a plurality of tongues 7 formed around the edge thereof, which tongues 7 are adapted to fit

in the elongated slots 5 formed along the lower edge of the end flaps 3. These tongues 7 are provided with ears 8 which are adapted to be flattened out after the 60 tongues 7 have been inserted through the slots 5 and thereby constitute an efficient means for holding the bottom closure flap in engagement with the end closure flaps. The ears 8 of the tongues 7 are of course 65 bent backwardly upon the main portion of the tongues 7 while the tongues are being inserted through the slots 5, but as stated above, after the tongues have been inserted through the slots 5, these ears 8 are then 70 spread outwardly thereby preventing the bottom closure flap from being disengaged from the end closure flaps.

As illustrated in Fig. 2, the bottom closure flap is provided with the slot 6 and the end 75 closure flaps 3 are provided with slots near the upper edges thereof for the purpose of receiving the tongues 9 carried by the top closure flap 4. These tongues 9 are provided with laterally extending ears 10 and 80 an elastic strip 11 is formed upon or secured to the bottom of each of the tongues 9 so as to overhang the inner faces of the ears 10 and normally hold these ears in an ex- 85 tended position.

It should be understood that the ears 10 may be folded to the position shown in dotted lines in Fig. 5 for the purpose of passing the tongues 9 through the slots 6. It of course should be understood that as 90 soon as the tongues 9 are passed through the slots 6 and the slots formed near the upper edges of the end flaps 3, the elastic strips 11 will cause the ears 10 of the tongues 9 to 95 assume the position shown in Figs. 5 and 6 and thereby prevent the upper flap 4 from 100 being opened without tearing the envelop. It should be understood that the slots 5 and 6 are formed so as to be the same width as the body portion of the tongues 7 and 9 and are not of sufficient length to permit the tongues 9 to pass through the slots when the ears 10 are in an extended position.

From the foregoing description it will be seen that a very simple and efficient mechanism has been produced for sealing the envelop which will prevent the envelop from being opened by unauthorized parties without being detected.

What I claim is:—

As a new article of manufacture, an envelop of the class described comprising a

body, said body provided with end flaps and upper and lower flaps, said end flaps provided with slots formed therein, tongues formed upon the peripheries of said top and bottom flaps, said tongues adapted to be passed through said slots formed in said end flaps for holding the envelop in a closed position, each tongue provided with ears adapted to be spread for preventing the withdrawal of the tongues from said slots,

and an elastic strip secured to the under faces of the tongues of said top flap and projecting over the under faces of the ears of said tongues of said top flap and adapted to normally hold said last-mentioned ears 15 in an extended position with respect to said last-mentioned tongues.

In testimony whereof I hereunto affix my signature.

JOHN MILUTIN.
